DIMENSION MEASURING OPTICAL SIGHTING DEVICE

Gerald E. Kerr, St. Louis, Mo., assignor to the United States of America as represented by the United States Atomic Energy Commission

Application December 12, 1955, Serial No. 552,666

2 Claims. (Cl. 88—14)

This invention relates to a sighting device.

In the production of metallic uranium from uranium fluoride, the latter and magnesium are heated to an elevated temperature in a steel container to which a special non-metallic lining has been applied. It is very important because of the elevated temperature that the lining have no thin spots that could permit uranium fluoride and magnesium being heated therein to damage the steel container. I propose to guard against undesirable thin spots in the lining by making sure that the lining is of uniform thickness.

I have invented a sighting device to check the uniformity of thickness of a lining applied to a container.

According to the present invention, I use the concentricity of the juncture of the sides and the base of the container with the juncture of the portions of the lining applied to the sides and the base of the container as an indication of the uniformity of thickness of the lining. The sighting device of the present invention checks the concentricity of the images projected by these junctures.

In the drawings:

Fig. 1 is an elevational view, partly in section, showing a lined container and the sighting device of the present invention applied thereto;

Fig. 2 is a plan view, with parts broken away and in section, of the sighting device and the lined container to which it is applied; and

Fig. 3 is a vertical sectional view taken on the line 3—3 showing the sighting device and the upper end of the lined container.

As shown in Fig. 1, a steel container 10 which is tubular and circular, has a lining 11 applied thereto, which lining may be a suitable material such as dolomite, slag, or limestone. The lining 11 may be applied by a process that involves jolting of the material into position between the container 10 and a mandrel, not shown, positioned in the container in spaced relation to the interior thereof. After application of the liner, the container 10 is filled with a charge, not shown, of UF_4 and Mg to a region near the top, a plug, not shown, of the same material as the lining 11 is placed in the top of the container on the mixture, and a steel cover, not shown, is secured to the container 10 by bolts or screws, not shown, going through holes 12 formed in a flange 13 on the upper open end of the container 10. Now the container and its contents are subjected to an elevated temperature such as 1200° F. for a time sufficient to reduce the UF_4 to U and to convert the Mg to MgF_2 . Afterwards the container cover and the plug are removed. Next the treated charge is removed for further processing. The lining 11 is scraped out of the container to make room for a new lining to be applied by a jolting process as described.

It is very important that the lining 11 not have thin spots that might allow the charge of UF_4 and Mg to damage the steel container 10 during the elevated temperature of the reduction process. To guard against thin spots in the lining 11, I have sought to assure that the

lining 11 is of uniform thickness. As a check on the uniformity of thickness of the lining 11, I have looked for concentricity of circular junctures 14 and 15 formed, respectively, between the sides and the base of the container 10 and between the sides and the base of the lining 11 in the container.

To carry out this novel method I make use of the novel sighting device 16, of the present invention, which I shall now describe. This device comprises a lens 17, 10 a glass 18 ground on its upper surface 19 upon which concentric inner and outer circles 20 and 21 are inscribed, upper and lower tubular sections 22 and 23 which support the glass 18 and lens 17 in adjustable spaced relation to one another, radial legs 24 extending outwardly 15 from the tubular section 22, and foot members 25 adjustably connected with the outer ends of the legs 24 for conjointly shifting the lens 17 and the ground glass 18 with respect to the container 10.

The lens 17 is attached to the lower side of a rectangular glass 26, which is clamped at its four corners between two rubber rings 27, which are held by upper and lower annular members 28 and 29. The lower annular member 29 is secured as by soldering or welding to the lower end of the tubular section 23. The glass 26 is 25 clamped between the rings 27 by means of the upper annular member 28 and bolts 30. The heads of these bolts engage the annular member 28, and threaded shanks of the bolts go through the lower annular member 29, and are engaged by nuts 31 drawn up against the bottom of the annular member 29. The lens 17, the glass 26, the rings 27, and the upper annular member 28 lie within the lower end of the tubular section 23 and above the lower annular member 29.

The ground glass 18 is clamped between two rubber rings 32 which are in turn clamped between upper and lower rings 33 and 34. The lower ring 34 is secured as by soldering or welding to the upper end of the tubular section 22. The upper ring 33 is held in place on the associated rubber ring 32 by means of threaded members 35, nuts 36 on the members 35, and washers 37 held by the nuts 36 against the upper ring 33. The threaded members 35 are secured to the exterior of the tubular section 22 and extend axially beyond the upper end thereof in spaced relationship to one another.

45 The inner ends of the legs 24 are secured as by soldering or welding to the outer surface of the tubular section 23 at its lower end, and to the outer ends of the legs 24 there are secured as by soldering or welding short internally threaded sleeves 38. These sleeves extended transversely to the legs 24 in parallelism with the tubular sections 22 and 23 and receive threaded shanks 39 of the foot members 25. Each foot member 25 also has an enlarged head 40 provided with a conical surface 41 and knurled surface 42. The foot members 25 are adjusted 50 with respect to the sleeves 38 by engagement of the knurled surfaces 42 or by the use of a screwdriver on screws 43 threaded into the ends of the shanks 39 of the foot members 25. The foot members can be held against movement by jam nuts 44 threaded on the shanks 39 against the ends of the sleeves 38.

60 In operation the sighting device 16 is placed on the container 10 when empty or unlined, as shown in the drawing, with the heads 40 on the three foot members 25 partially entering the three openings 12 in the container flange 13. The foot members 25 are individually 65 adjusted and the spacing between the glass 18 and the lens 17 is varied by angular movement of the tubular section 22 with respect to the tubular section 23 until the image of the circular juncture 14 between the sides and bottom of the can 10 is brought into focus on the upper ground surface 19 on the glass 18 and into coincidence with the outer circle 20 on the surface 19. The

jam nuts 44 are tightened against the sleeves 38 to hold the foot members 25 against movement. Now the sighting device 16 is removed from the container flange 13, and lining 11 is applied to the interior of the can as previously described.

Now the sighting device 16 is reapplied to the container flange 13 in the same way it was originally applied thereto, the conical heads 40 of the foot members 25 being set in the same respective openings as before. This must necessarily occur, because the legs 24 are not equally spaced from one another at 120° but have a slightly different spacing that may be 108°-144°-108°. The openings 12 in the container flange 13 will of course have this same opening.

Now the spacing between the glass 18 and the lens 17 is adjusted by angular movement of the tubular section 22 with respect to the tubular section 23 until the image of the circular juncture 15 formed between the sides and the base of the lining 11 comes into focus on the ground surface 19 on the glass 18. If the image of the juncture 15 coincides with the inner circle 21 on the glass 18, it is presumed that the thickness of the sides of the lining is uniform and there are no thin spots. This may also be presumed of the image if the juncture 15 is concentric with the inner circle 21, but for a predetermined thickness of the sides of the lining coincidence should occur.

It is also understood that the invention is not to be limited by the details given herein but that it may be modified within the scope of the appended claims.

What is claimed is:

1. A sighting device comprising two tubular sections having their inner ends in threaded connection with one another, a lens, a rectangular glass secured to the lens, a pair of annular members clamping the rectangular glass at the corners, means attaching one annular member to

the outer end of one tubular section, the other annular member, the lens, and the rectangular glass lying within said outer end of the said one tubular section, a ground glass inscribed with two concentric circles and being 5 positioned at the outer end of the other tubular section, two rings applied to opposite sides of the ground glass at the periphery thereof, one ring engaging the outer end of the said other tubular section, threaded members 10 fixed to the exterior of the said other member in circumferentially spaced relationship to one another and projecting beyond the outer end of the said other member, washers applied to the threaded members against the other ring, and nuts engaging the threaded members against the washers, and supporting means acting between the said one tubular section and the object upon 15 which the sighting device is to operate for conjointly tilting the lens and the ground glass with respect to the object.

2. The sighting device specified in claim 1, the supporting means comprising three generally radial legs having their inner ends attached to said one tubular section, short threaded sleeves attached to the outer ends of the legs so as to extend transversely thereto, and foot members having threaded shanks extending through the 20 sleeves in threaded engagement therewith and enlarged conical heads engageable with recesses in an object upon which the sighting device is to operate.
